CLAIM

The ornamental design for a window sash takeout cover, as shown and described.

DESCRIPTION

FIG. 1 is a perspective view of a window sash takeout cover showing our new design;

FIG. 2 is a top plan view thereof;

FIG. 3 is a front elevational view thereof;

FIG. 4 is a bottom plan view thereof; and

FIG. 5 is left side elevational view thereof, the right side being a mirror image of the left.
